UNITED STATES PATENT OFFICE.

RICHARD F. BARRY, OF NEWTON, MASSACHUSETTS.

DESIGN FOR A BELT.

SPECIFICATION forming part of Design No. 32,419, dated March 27, 1900.

Application filed February 26, 1900. Serial No. 6,646. Term of patent 3½ years.

To all whom it may concern:

Be it known that I, RICHARD F. BARRY, of Newton, in the county of Middlesex and State of Massachusetts, have invented and produced 5 a certain new and original Design for a Belt, of which the following is a specification, reference being had to the accompanying drawings, forming a part thereof.

Figure 1 represents a side view showing the 10 outer side of the belt. Fig. 2 represents a similar view showing the inner side.

As shown in the drawings, the leading or material feature of my design is the center 15 piece *a*, extending across the central portion of the belt *b*, and the end pieces *c c*, extending across the end portions. The belt decreases

in width from the central portion to the ends, and the end pieces *c c* are shorter than the center piece. The center piece and the end pieces are ornamented by circular eyelet- 20 heads *d d*, and the center piece is additionally ornamented by crossed cords *e e*.

I claim—

The design for a belt, substantially as herein shown and described. 25

In testimony whereof I have affixed my signature in presence of two witnesses.

RICHARD F. BARRY.

Witnesses:

C. F. BROWN,
A. D. HARRISON.
